(57) **CLAIM**

The ornamental design for a self injection device, as shown and described.

DESCRIPTION

FIG. 1 is a perspective view of an embodiment of a self injection device showing our new design, with a cap shown in a secured position;
FIG. 2 is a front elevational view of the self injection device shown in FIG. 1;
FIG. 3 is a top view of the self injection device shown in FIG. 1;

FIG. 4 is a left side elevational view of the self injection device shown in FIG. 1;

FIG. 5 is a right side elevational view of the self injection device shown in FIG. 1;

FIG. 6 is a bottom view of the self injection device shown in FIG. 1; and,

FIG. 7 is a rear elevational view of the self injection device shown in FIG. 1.

1 Claim, 3 Drawing Sheets(56)
